UNITED STATES PATENT OFFICE.

CHAUNCEY E. DEWEY, OF DENVER, COLORADO, ASSIGNOR TO THE AMERICAN ZINC AND CHEMICAL COMPANY, OF DENVER, COLORADO.

ROASTING OR OXIDIZING FURNACE.

No. 828,095.

Specification of Letters Patent.

Patented Aug. 7, 1906.

Application filed September 16, 1904. Serial No. 224,710.

To all whom it may concern:

Be it known that I, CHAUNCEY E. DEWEY, a citizen of the United States, residing in the city and county of Denver and State of Colorado, have invented certain new and useful Improvements in Roasting or Oxidizing Furnaces; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in roasting-furnaces or furnaces adapted for use in roasting or oxidizing ores for the purpose of removing their refractory elements or impurities—such as sulfur, arsenic, and other elements—which render it difficult to treat them for the separation of their metallic values.

Under the old practice it is found impossible to thoroughly roast ore high in silica or not sufficiently high in sulfur without supplying heat from a grate or other source independent of the combustible elements carried by the ore.

My invention relates to the treatment of this class of ores—that is to say, where the silica is so high or the sulfur is combined with the metals in such a manner as to burn out considerably during the earlier stage of the roasting, whereby not enough sulfur remains to supply heat by combustion with the oxygen of the air to finish the oxidizing process.

My invention depends for its success upon the feeding of the ore into the furnace at such a point as to take advantage of the excess or waste heat of the earlier stage of the roasting to supply the required heat for final roasting or oxidation, and it is done by having the finishing-hearth above the hearth where the ore was first introduced, thus allowing the heat from below to radiate through the finishing-hearth to the ore or by directing the hot combustion-gases from the chamber or furnace compartment where the ore was first introduced to the finishing chamber or compartment through suitable flues and ports. I also provide means for regulating the draft through the central hollow shaft to prevent undue radiation from the finishing-hearth

and to control in this way to a great extent the temperature throughout the furnace. 55

My improved furnace belongs to the class composed of a vertical cylinder provided with hearths arranged within the cylinder one above another and provided with a centrally-located hollow shaft, with which the rabble-arms or the arms carrying the plows or stirrers are detachably connected.

My improvement consists in constructing a furnace of this class in such a manner that the raw ore is first introduced in the lower part of the furnace in order that this part of the furnace may be made and kept hottest. After the ore has passed through the lower part of the furnace it is discharged into a bucket and elevated to the top of the furnace and charged upon the uppermost hearth. This furnace is so constructed that the ore is gradually worked from the upper to the lower hearths in succession, the roasted ore being finally taken out of the furnace from the hearth above that on which it was originally charged. Assuming that the raw ore is introduced into the furnace upon the second hearth from the lowermost, the ore will be finally taken out from the hearth immediately above. Hence by reason of the introduction of the raw ore into the lower part of the furnace the heat due to the combustion of the sulfur and other elements in the ore is greatest in this part of the furnace, and as the ore which is introduced upon the uppermost hearth moves downwardly the heat to which it is subjected is continually increasing, and this is as it should be, since after the ore is deprived of the greater part of its sulfur it is subjected to the heat generated during the earlier stage of the operation, thus satisfactorily desulfurizing these ores without the use of other fuel. In other words, according to the old method or process of operating this style of furnace the raw ore is introduced originally upon the uppermost hearth. Hence the heat resulting from the combustion of the sulfur and other elements is greatest in the upper part of the furnace by reason of the fact that the raw ore supplies a greater quantity of fuel when first introduced than at any subsequent time. The result is that as the ore moves downwardly under the old practice the heat of the furnace diminishes, and it becomes impossible to perfectly roast

90

105

the ore by reason of the fact that the lower part of the furnace is not kept at a sufficiently high temperature to remove the remaining impurities when the ore has reached the lower part of the furnace. My invention is intended to overcome this difficulty in the manner above explained. In this style of furnace the centrally-located hollow shaft is rotated for the purpose of rotating the rabbles, which are moved over the hearths and so constructed and arranged as to cause the ore to travel in opposite directions on any two adjacent hearths—that is to say, if it travels inwardly on an upper hearth it drops downwardly through a central opening in the hearth to the central portion of the hearth next below, from which it is gradually made to travel outwardly on the hearth and discharged through openings therein to the outer portion of the hearth next below, on which it is again made to travel inwardly, and so on, thus taking a zigzag course until the finishing-hearth is reached, from which the ore is discharged in a completely roasted or oxidized condition.

Having briefly outlined my improved construction, as well as the function it is intended to perform, I will proceed to describe the same in detail, reference being made to the accompanying drawings, in which is illustrated an embodiment thereof.

In the drawings, Figure 1 is a side elevation of a furnace equipped with my improvements. Fig. 2 is a vertical section taken through the furnace approximately on the line 2 2, Fig. 3. Fig. 3 is a top plan view of the furnace. Fig. 4 is a fragmentary vertical section of the furnace. Fig. 5 is a fragmentary side elevation of the furnace, taken from a point located at the right of Fig. 2. Fig. 6 is a sectional view taken through the feed hopper, from which the raw ore is fed to the furnace, the parts being shown on a larger scale. Fig. 7 is a sectional view taken through the hollow shaft, showing one of the rabbles in place, the parts being shown on a larger scale. Fig. 8 is a section taken on the line 8 8, Fig. 7. Fig. 9 is a similar view showing the rabbles in a different position from that shown in Fig. 8. Fig. 10 is a detail view illustrating the bucket and bucket-carrier at its extreme upward limit of movement. A portion of the furnace is also shown in this view. Fig. 11 is a detail view of the bucket-carrying mechanism viewed from a position at the right of Fig. 10, the bucket, however, being shown in a lower position than in Fig. 10. Fig. 12 is a fragmentary side view of the furnace, showing the bucket and its carrier in a lower position than in Fig. 11 and in position to cause the bucket-filling chute to assume the inclined position as the bucket continues its downward movement. Fig. 13 is a similar view showing the bucket at its extreme lower position and the

chute in position to discharge into the bucket. Fig. 14 is a detail view of the lower part of the bucket-carrier track, together with the pivoted chute and its pendant.

The same reference characters indicate the same parts in all the views.

Let the numeral 5 designate the outer shell, and 6 the brick lining forming the vertical wall of the cylindrical body of the furnace. This furnace is provided with a number of hearths located one above the other. If we designate the bottom or lowermost hearth as A, the other hearths may be designated A', A'', A''', A''', and A'', respectively, counting from the bottom upwardly. It will thus be observed that the bottom of the furnace forms the lowermost hearth. Above the uppermost hearth is a wall A'', which may be said to constitute the top of the furnace. Through the center of this furnace, which is open for the purpose, extends a hollow shaft B, provided with sockets adapted to receive arms C, provided with plows or rabbles D. There are two rabbles connected with this hollow shaft for each hearth of the furnace, and the plows or rabbles are so arranged as to cause the material on the hearths to travel alternately inwardly and outwardly on any two successive hearths, as heretofore explained. It will not be necessary to illustrate this feature in detail, since the rabbles of all furnaces of this style or type are arranged in this manner. The sockets which receive the rabbles are formed in pairs by inserting transversely in the hollow shaft B a tube E, which is smallest at the center and increases in diameter outwardly in both directions, forming two sockets. The rabbles C are formed to fit these sockets. Near the outer extremity of each socket is formed a lug G, which occupies the lower part of the socket. Each rabbles is flat on its lower side, as shown at C', and the portion of the arm which enters the socket is provided with a lug C'', which when the arm is fully inserted in the socket of the hollow shaft occupies a position just inside of the lug G of the socket.

When it is desired to insert the rabbles in the socket, it is turned to the position shown in Fig. 9, which brings the lug B'' of the arm just above the lug G of the socket. This allows the rabbles to be inserted in the socket, its flat side being then on an incline, as shown in the said figure. After insertion the rabbles is turned to bring its flat side in a horizontal position, or into the position shown in Fig. 8, in which event the lug B'' of the arm occupies a position just inside of the lug G of the socket, and a portion of the flat side of the arm rests on the upper horizontal edge of the lug G. (See Fig. 8.) This lug G forms a stop to prevent the rabbles from moving farther in that direction, and the travel of the rabbles in the furnace is such that the pressure of the ore

on the plows serves to hold the rabble-arms in this position—that is to say, whereby the flat sides of the arms are caused to engage the stops G. The rabble-arm is thus securely held in position and cannot be pulled outwardly until it is given a partial rotation, whereby it is made to assume the position shown in Fig. 9. In other words, the operation of removing the arm is exactly the reverse of inserting it.

To the lower extremity of the hollow shaft B is attached a gear 7, which meshes with a pinion 8, fast on a shaft 9, journaled in a suitable support 10 and provided at its outer extremity with a worm-wheel 11, actuated by a worm 12, whereby a comparatively slow rotary movement is imparted to the hollow shaft and the rabble-arms connected therewith.

The central opening at the bottom of the furnace or the lowermost hearth A is provided with a tubular lining 13, which projects slightly above the upper surface of the hearth and co-operates with a cap 14, attached to the hollow shaft, whereby there is practically no communication around the shaft with the outer air at the bottom of the furnace. The hollow shaft, however, is provided with orifices just above the gear 7, whereby the air is allowed to enter the shaft and pass upwardly freely therethrough for cooling purposes. The hearth A' is provided with an opening 15, surrounding the shaft, whereby the ore is allowed to pass from the hearth A' to the hearth A and whereby the heat and products of combustion are allowed to pass upwardly from the lowermost chamber to the chamber next above. The chambers of this furnace, named in their order from the bottom to the top may be designated 16, 17, 18, 19, 20, and 21, respectively. From the chamber 17 there is no direct communication with the chamber 18. There is, however, an opening 21^a at one side of the chamber 17, which leads to a flue 22, formed in the wall of the furnace at one side and extending upwardly to the uppermost chamber of the furnace. The top of this flue may be closed by a cover 23, which is removable at pleasure. The flue 22 communicates with the chamber 18 by means of an opening 24, through which the heat and products of combustion from the lower chambers of the furnace may be caused to enter the chamber 18 and pass upwardly through the opening 15^a in the center of the hearth A³ into the chamber 19, from which the heat and products of combustion may pass through the opening 25 to the chamber 20 and thence through the central opening 15^c to the chamber 21, or the uppermost chamber of the furnace, from which point they may escape through a flue 26, which leads to the stack. (Not shown.) The furnace may also be provided with an auxiliary outlet by way of an opening 27 at

one side of the uppermost chamber 21 to a flue 28, which, however, may be closed by a removable cap 29. Each of the hearths A² and A⁴, as well as the top A⁶ of the furnace, is provided with means similar to that already described and designated 13 and 14 to prevent communication between the adjacent chambers around the hollow shaft or between the uppermost chamber and the atmosphere. As there is nothing new, however, about this construction it need not be explained further in detail.

To the outer extremity of the shaft 9, beyond the worm-wheel 11, is made fast a sprocket-wheel 30, which is connected, by means of a chain 31, with a sprocket-wheel 32, mounted on a spindle 33, suitably supported on the outer wall of the furnace. A hub 34 is directly and loosely mounted on the spindle 33, and the sprocket 32 is made fast to the said hub. The hub 34 is provided with a crank 35, in whose outer extremity is made fast a pin 36, upon which two pulleys 37 are loosely mounted. These pulleys are connected, by means of a cable 38, with two similar pulleys 39, loosely mounted on a spindle 40, secured to the outer wall of the furnace and at the top thereof. The cable 38 passes from the upper pulleys 39 over a guide-pulley 41, thence upwardly over another pulley 42, mounted on the upper extremity of a vertical track 43, upon which is slidably mounted a bucket-carrier 44, with which one extremity of the cable 38 is connected after leaving the pulley 42. The track 43 consists of two twin parts or members 43^a suitably separated, upon which is mounted the bucket-carrier 44, as aforesaid. This bucket-carrier is of skeleton construction and is provided with two separated members 44^a, bowed outwardly from the track and whose extremities 44^c are shaped to fit the outer edges of the track and arranged to slide freely thereon. The two members 44^a are connected by cross-pieces 44^d and also by an upper cross-piece 44^e, to which the cable 38 is connected. By reason of the bowed construction of the bucket-carrier a sufficient space is formed between the track members and the parts 44^a of the carrier to make room for the bucket 45, which is pivotally connected with the frame at its outer lower extremity, as shown at 46, whereby it is adapted to swing inwardly when permitted to do so by the track members 43^a. For the greater part of their length the members 43^a are of sufficient width to cause the bucket to occupy an upright position. When, however, it is raised to the top of the furnace, or to the position shown in Fig. 10, it reaches a point of the track where its members are cut away or recessed, as shown at 43^c, thus making the space between the two track members of sufficient width to allow the bucket to turn on its pivot 46 and assume the position 130

indicated by dotted lines in Fig. 10, whereby its contents are discharged into an opening 47, formed in the upper part of the furnace-wall and communicating with the uppermost chamber 21, whereby the ore to be treated is discharged upon the uppermost hearth A.

From the explanation just given it will be understood that as the sprocket-chain 31 is actuated by the rotation of the shaft 9 the sprocket 32 will be set in motion and the crank 35 will be turned, the center of its pin 36, or that upon which the pulleys 37 are mounted, describing a path indicated by the dotted circle 48. During this movement of the crank and the pulleys 37 from the uppermost to the lowermost point of their circular path it will be understood that the length of cable required to connect the two pulleys 37 with the two pulleys 39 will be increased sufficiently to draw the bucket-carrier upwardly. This construction is so arranged that during the travel of the pulleys 37 from the highest to the lowest point of their path the bucket-carrier will be drawn from its lowermost to its uppermost position, allowing the bucket to dump or assume the position indicated by dotted lines in Fig. 10, as heretofore explained, while during the movement of the pulleys 37 from the lowermost point to the uppermost point of their path the bucket-carrier and the bucket will be allowed to descend from their uppermost to their lowermost position.

At the outer edge of the lowermost hearth, or that designated A in the drawings, is formed an inclined passage 49, with which is connected a correspondingly-inclined conduit 50, which extends somewhat below the bottom of the furnace and to whose lower extremity is pivotally connected, as shown at 51, a chute 52, with which is connected a weight 53. Pivotally connected with the pivoted chute at its outer extremity, or that remote from the weight, as shown at 54, is a pendant 55, having a part 56 projecting outwardly at right angles to the arms of the pendant and located in the path of the bucket 45 as the latter descends. As the bucket moves downwardly the pivoted chute is normally held by its weight 54 in its inactive position or in position to close the lower extremity of the conduit 50. When, however, the bucket reaches the position shown in Fig. 12, its bottom engages the part 56 of the pendant 55, and as the bucket and its carrier continue their downward movement the chute is thrown to the operative position shown in Fig. 13, whereby the contents of the conduit are allowed to discharge into the bucket 45, whereby the latter is filled or loaded. The bucket and its carrier then immediately begin their upward movement, and the pivoted chute 52 is allowed to resume its conduit-closing position, (shown in Fig. 12,) as will be readily understood. At-

tention is called to the fact that the part 56 of the pendant is sufficiently narrow to pass between the track members 43, whereby the carrier in its upward and downward movement has no action on the said pendant part; but the latter is acted on by the bucket during its downward movement, as heretofore explained. It will thus be understood that as the bucket and its carrier move upwardly the pendant and the chute 42 will be allowed to resume the position shown in Fig. 12.

The material to be treated is placed in a hopper 57, mounted on a cylindrical casing 58, secured to the outer wall of the furnace and whose inner extremity communicates with an inclined passage 59, leading downwardly into the chamber 17. In this casing 58 is journaled the shaft 60 of a feed-screw 61. This shaft protrudes from the casing, and upon one end thereof is mounted a ratchet-wheel 62, which is fast thereon. Loosely mounted on the protruding extremity of the shaft is a depending lever 63, whose upper extremity is bifurcated to engage the shaft and straddle the ratchet-wheel. This lever is provided with a dog 64, which engages the ratchet-wheel and imparts an intermittent movement to the feed-screw as the depending lever-arm is oscillated. This lever 63 is slotted to receive one extremity of an arm 65, whose opposite extremity is fast on a vertical shaft 66, journaled in suitable bearings mounted on the outer wall of the furnace. The lower extremity of the shaft 66 is provided with a crank 67, which is connected with one extremity of a pitman 68, whose opposite extremity is connected with a disk 69 at a suitable point 70 outside of its center, whereby as the disk is rotated a reciprocating movement is imparted to the pitman and partial rotary movements in reverse directions to the shaft 66. As this shaft 66 is actuated it is evident that a corresponding movement will be given to the arm 65, which will impart an oscillating movement to the lever 63, whereby the feed-screw will be intermittently actuated, as heretofore explained. This movement of the feed-screw will discharge the ore into the chamber 17 of the furnace. The disk 69 is fast on one extremity of the shaft 9.

The ore when completely roasted is discharged from the chamber 18 of the furnace through a passage 71, formed in the wall of the furnace and communicating with a chute 72, attached to the outer wall thereof. This roasted ore may be discharged into any suitable receptacle.

The outer wall of the furnace is provided with openings communicating with the several chambers. These openings are preferably arranged in a diagonal line, as shown in Fig. 1, and each is normally closed by a door 73. As these openings and their respective doors are arranged in different ver-

tical planes, they are more conveniently accessible than if they were arranged one directly above another, since it is desirable to have a ladder for each opening, whereby the latter is made conveniently accessible to the person or persons in charge of the furnace. If these doors and their respective openings were arranged one directly above another, there would be considerable difficulty in gaining access to them.

From the foregoing description the use and operation of my improved roasting or oxidizing furnace will be readily understood. The ore to be treated is first fed from the hopper 57 to the chamber 17, or the second chamber from the bottom of the furnace. The ore thus discharged into this chamber falls upon the hearth A' and is acted on by the rabbles of the said chamber, since rotary movement is imparted to the shaft B preparatory to the commencement of the operation. The ore in this chamber is originally ignited from any suitable source. Assuming that the initial heating of the furnace is sufficient to ignite the sulfur and other impurities in the original charge of ore, the operation is continued without the further supply of fuel, since the sulfur and other combustible impurities of the ore are sufficient in quantity to sustain the heat of the furnace. The ore falling upon the hearth A' is gradually worked by the action of the rabbles toward the center of the furnace and passes through the central opening 15 to the chamber 16 below. The ore in this chamber 16 is also acted on by the rabbles, but is gradually worked outwardly and discharged by way of the conduit 50 into the chute 52 and thence into the bucket 45 as partially-roasted ore. This ore is then carried upwardly in the bucket and discharged into the uppermost chamber of the furnace in a manner heretofore explained. Having reached the uppermost chamber, or that designated 21 in the drawings, the ore is gradually worked toward the center of the furnace and discharged through the opening 15^a to the chamber 20 next below, in which it is acted on by the rabbles and carried outwardly, being discharged to the chamber 19 through openings 25 in the outer edge of the hearth adjacent the inner wall of the furnace. While only one of these openings is shown in the drawings, a number will be used in practice. After the ore reaches the chamber 19 it is again carried by the rabble mechanism toward the center of the furnace and discharged through the opening 15^a into the chamber 18, where it is again acted on by the rabbles and carried outwardly, being discharged in a completely-roasted condition through the outlet 71, as heretofore explained.

Attention is called to the fact, as heretofore intimated, that the ore may be fed either to the center or the outer edge of the upper-

most hearth, whereby it may be caused to travel in the first instance either outwardly or inwardly, as may be desired. In any event the travel of the ore on the hearth next below will be in a direction opposite that from which it traveled on the hearth next above. As shown in the drawings, (see Fig. 2,) the central hollow shaft B is provided with an extension at the top, in which a damper H is located for the purpose of controlling the draft from the furnace. Under some circumstances the draft of air through this central hollow shaft, if unobstructed, may have an undue cooling effect upon the furnace. The function of the damper is to regulate this draft according to circumstances. If it is desired to direct the combustion-gases through the chambers of the furnace above the chamber 17, into which the ore is first charged, the flue 22 is closed at the top, whereby these gases are compelled to pass through the port or passage 24 to the chamber 18, thence upwardly through the opening 15 of the hearth A³ into the chamber 19 above, whence they are caused to travel outwardly, and so on, the combustion-gases in this case taking a zigzag course through the furnace in a direction opposite that of the downward travel of the ore from the top of the furnace to the finishing hearth or chamber.

Having thus described my invention, what I claim is—

1. In a furnace of the class described, the combination with a centrally-located revolvable shaft and rabble-arms adapted to enter sockets with which the shaft is provided, each socket being provided with a lug, located in its lower portioa and each rabble-arm being flattened on one side and also provided with a lug, the rabble-arms being also adapted to turn in the sockets of the shaft, the lugs of the rabble-arm and socket being so arranged that by giving the arm a partial turn it may be inserted to bring its lug inside of the plane of the socket-lug, whereby when the arm is turned to bring its plows into the operating position, its lug will occupy a position inside and engaging the lug of the socket to prevent the removal of the arm by a direct outward movement, and to hold plows in an upright position.

2. In a furnace of the class described, the combination of a centrally-located vertical shaft provided with sockets, each socket having a lug, rabble-arms adapted to enter the sockets of the shaft, each arm being flattened on one side and provided with a lug arranged to cooperate with the lug of the socket, to prevent the removal of the arm by a direct pull, substantially as described.

3. A roasting-furnace of the class described, provided with an inlet for the raw ore communicating with one of its lower chambers, the said chamber being provided

with a lateral outlet communicating with a flue formed in the outer wall of the furnace, the chamber next above that into which the raw ore is charged being provided with an 5 opening communicating with the said vertical flue, and a suitable cover adapted to close the upper extremity of the flue whereby the products of combustion may be compelled to pass through the upper chambers of 10 the furnace if desired for increasing the temperature.

4. A furnace of the class described provided with intercommunicating chambers arranged one above another, the furnace having 15 an inlet for the raw ore communicating with one of the lower chambers, an outlet leading from its lowermost chamber, an inlet for the partially-roasted ore communicating with the uppermost chamber, a suitable track 20 mounted outside of the furnace, a bucket-carrier mounted on said track, a bucket pivotally connected with said carrier, a chute connected with the outlet from the lowermost chamber of the furnace, a conduit registering 25 with said outlet but with whose lower extremity the chute is pivotally connected, the chute being weighted to normally close the lower extremity of the conduit and provided with a part located in the path of the 30 bucket as the latter descends, whereby the chute is thrown downwardly to permit the ore to be discharged into the bucket, and suitable means for elevating the bucket and its carrier, the bucket being so connected 35 with the carrier that its tendency is to assume the dumping position, the upper part of the track being cut away to allow the bucket to tip inwardly when it has been raised to a position to discharge into the 40 inlet to the uppermost chamber of the furnace.

5. A furnace of the class described provided with an outlet communicating with one of its lower chambers, and an inlet communicating with one of its upper chambers, 45 a conduit connected with the said outlet, a chute pivotally connected with the lower end of the conduit and weighted to cause it normally to occupy a position to close the lower extremity of the conduit, the said chute having 50 a part projecting into the path of the bucket as the latter descends, an upwardly-projecting track, a carrier mounted to travel on the said track, a bucket located in said carrier and pivotally connected with the latter beyond its center whereby there is a tendency of the bucket to tip inwardly, the track being constructed to cause the bucket to assume an upright position except at its upper part where the track is cut away to allow the 55 bucket to tip inwardly and discharge into the inlet communicating with the uppermost chamber.

6. In a furnace of the class described, the combination of the body of the furnace provided with chambers arranged one above an-

other, a vertical shaft centrally located in the furnace and arranged to rotate, rabble-arms connected with the said shaft and provided with suitable plows or stirrers, a shaft suitably journaled below the furnace, an operative gearing-connection between the said shaft and the rabble-arm shaft of the furnace, an upwardly-projecting track arranged outside of the furnace and consisting of two separated members, an outlet-conduit communicating with the lowermost chamber of the furnace and extending downwardly therefrom, a chute pivotally connected with the lower extremity of the conduit and weighted to cause it to occupy a position to close the lower extremity of the conduit, the said chute having a depending part projecting into the space between the two members of the track, a bucket-carrier slidably mounted on the track members, a bucket pivotally connected with said carrier whereby there is a tendency of the bucket to tip inwardly, the width of the bucket being such that during the greater part of its travel it engages the members of the track whereby it is prevented from tipping inwardly, the upper part of the track members being cut away to allow the bucket to tip inwardly when it has reached a suitable elevation, and a suitable operating connection between the operating- 90 shaft and the bucket-carrier whereby the latter is alternately raised and lowered, the part of the chute projecting into the space between the two members of the track, lying in the path of the bucket as the latter descends, 95 whereby the chute is carried downwardly to allow the contents of the conduit to discharge into the bucket.

7. In a furnace of the class described, the combination of the furnace-body provided with a number of chambers arranged one above another, a centrally-located vertical shaft mounted to rotate, rabble-arms connected with the shaft and equipped with suitable plows or stirrers, a horizontal operating-shaft located below the furnace, a gearing connection between the operating-shaft and the vertical shaft of the furnace, suitable means for actuating the operating-shaft, a crank revolvably mounted on the outer wall 115 of the furnace, a suitable operating connection between the said crank and the horizontal operating-shaft whereby the crank is rotated, a plurality of pulleys mounted on the said crank and arranged to travel therewith, corresponding pulleys mounted on the upper part of the furnace, a cable connecting the two sets of pulleys, an upwardly-projecting track arranged outside the furnace, a bucket-carrier mounted on said track, the said cable 120 being connected with the bucket-carrier, and suitable guides for the cable between the uppermost set of pulleys and the bucket-carrier.

8. In a furnace of the class described, the

combination of the body of the furnace provided with chambers arranged one above another, a vertical shaft centrally located in the furnace and arranged to rotate, rabble-arms 5 connected with the said shaft and provided with suitable plows or stirrers, a shaft suitably journaled below the furnace, an operative 10 bearing connection between the said shaft and the rabble-arm shaft of the furnace, an upwardly-projecting track arranged outside of the furnace and consisting of two separated members, an outlet-conduit communicating with the lowermost chamber of the furnace and extending downwardly therefrom, a chute pivotally connected with the lower extremity of the conduit and weighted 15 to cause it to occupy a position to close the lower extremity of the conduit, the said chute having a depending part projecting 20 into the space between the two members of the track, a bucket-carrier slidably mounted on the track members, a bucket pivotally connected with said carrier whereby there is a tendency of the bucket to tip inwardly, a 25 guide to prevent the bucket from tipping inwardly until it has reached a suitable elevated point where the guide is constructed to allow the bucket to assume the dumping position, and a suitable operating connection between the operating-shaft and the bucket- 30 carrier whereby the latter is alternately raised and lowered, the part of the chute projecting into the space between the two members of the track, lying in the path of the 35 bucket as the latter descends, whereby the chute is carried downwardly to allow the contents of the conduit to discharge into the bucket.

In testimony whereof I affix my signature in presence of two witnesses.

CHAUNCEY E. DEWEY.
